(57) **CLAIM**

The ornamental design for a keypad, as shown and
described.

DESCRIPTION

FIG. 1 is a front perspective view of a keypad showing our
new design;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is an enlarged view of a portion of FIG. 1;

FIG. 8 is a front perspective view of a second embodiment
thereof;

FIG. 9 is a front view thereof;

FIG. 10 is a left side view thereof;

FIG. 11 is a right side view thereof;

FIG. 12 is a top view thereof;

FIG. 13 is a bottom view thereof;

FIG. 14 is a front perspective view of a third embodiment
thereof;

FIG. 15 is a front view thereof;

FIG. 16 is a left side view thereof;

FIG. 17 is a right side view thereof;

FIG. 18 is a top view thereof; and,

FIG. 19 is a bottom view thereof.

The contour of the buttons in FIGS. 8-19 is the same as the
contour of the buttons in FIGS. 1-7.

In FIG. 7, the broken lines encircle a portion of the claimed
design that is illustrated in an enlargement.

The dark gray shading represents a matte surface, not
surface ornamentation or any particular color.

The light gray shading represents a reflective/shiny surface,
not surface ornamentation or any particular color.

1 Claim, 13 Drawing Sheets
